UNITED STATES PATENT OFFICE.

JOHN H. MORGAN, OF EAST ST. LOUIS, ILLINOIS, ASSIGNOR OF ONE-HALF TO SAMUEL C. JUMP, OF EAST ST. LOUIS, ILLINOIS.

RAIL-JOINT ADJUSTER.

Application filed March 10, 1927. Serial No. 174,206.

This invention relates to devices of the kind that are used for separating two longitudinally aligned rails for any purpose, as, for example, to facilitate the insertion or removal of an insulated end post between the rails, or for pulling two longitudinally-aligned rails together so as to reduce the width of the space or joint between the rails.

One object of my invention is to provide a rail joint adjuster which is of such design that a train can pass over the rails that are being adjusted without the necessity of disconnecting the adjuster from the rails.

Another object is to provide a rail joint adjuster that is light enough in weight to be carried by a single workman and which is of such design that one workman can operate it easily to separate two rails or pull the rails together.

Another object is to provide a rail joint adjuster which is of such design that when it is arranged in operative relationship with the rails it will not interfere with the insertion or removal of an insulating end post between the ends of the rails.

And still another object is to provide a rail joint adjuster, which, in addition to having the desirable characteristics above pointed out, is inexpensive to manufacture, and rugged enough to successfully withstand the excessive strains to which such devices are subjected in the operation of adjusting two longitudinally-aligned rails.

To this end I have devised a rail joint adjuster which is adapted to be arranged at one side of two longitudinally-aligned rails, so that it extends across the joint between the ends of the rails, means for connecting said member to one of the rails, and a tapered device that is adapted to be forced between an abutment means or surface on said member and the edge of a bolt hole in the other rail, so as to produce relative longitudinal movement between said member and said other rail.

Figure 1 of the drawings is a perspective view, illustrating my improved rail joint adjuster arranged in operative relationship with two longitudinally-aligned rails that are being adjusted.

Figure 2 is a top plan view, partly in horizontal section of the structure shown in Figure 1.

Figure 3 is a vertical transverse sectional view, taken on the line 3-3 of Figure 2; and

Figure 4 is a view similar to Figure 2, illustrating the method of using the adjuster to produce a relatively great movement between the two rails with which the adjuster is used.

Referring to the drawings which illustrate the preferred form of my invention, A and B designate two longitudinally-aligned rails whose ends are separated from each other by an open space or joint α , as shown in Figure 1. In an insulated rail joint an end post of insulating material, that conforms to the cross-sectional shape of the rails, is arranged in the space α between the ends of the rails. My improved adjuster is adapted to be used for forcing the rails A and B apart, so as to facilitate the removal or insertion of such an insulating end post between the rails, and it is also adapted to be used for pulling two longitudinally-aligned rails together, so as to close up or reduce the width of the space between the ends of the rails.

The adjuster comprises a member C that is arranged longitudinally of the rails at one side of same after the splice bars, fish plates or rail joint members have been removed from the rails, said member C being preferably constructed so that it will fit in between the heads and base flanges of the rails and bear against one side of the webs of the rails. The member C is connected to one of the rails, preferably by bolts 1 that pass transversely through said member and through the web of the rail A, so as to hold said member and rail in rigid relationship. Relative longitudinal movement between the rails A and B either to increase or decrease the width of the joint between said rails is produced by driving a tapered device D through a space in the member C and through a bolt hole 2 in the web of the rail B that are slightly offset with relation to each other or disposed in such relation that pressure which said tapered device D exerts on the edge of said bolt hole will produce relative longitudinal movement between the rail B and the member C.

In the preferred form of my invention, as herein illustrated, the portion of the member C that laps over the rail B is provided with an adjustable means that forms a space or passageway for the tapered device D and which can be set in various positions so as to vary the degree of longitudinal movement imparted to the rail B and also enable said

rail to be moved progressively or with a step by step movement relatively to the rail A. The adjustable means just referred to on the member C forms an abutment surface 5 against which the tapered device D bears when said device is exerting pressure on the edge of the bolt hole in the web of the rail B, and said means can be constructed in various ways without departing from the 10 spirit of my invention. In the preferred form of my invention, as herein illustrated, said means is formed by a plurality of shims or filler plates 3 that are mounted in a pocket in the member C in such a manner that 15 they can be adjusted longitudinally of said pocket, so as to form a transverse space in the member C that is slightly offset with relation to one of the bolt holes 2 in the web of the rail B. Consequently, when the tapered device D is inserted in said space and 20 then driven into the bolt hole 2 in the web of the rail B, said tapered device D will exert pressure on the edge of said bolt hole in a direction tending to move the rail B 25 longitudinally so as to bring the bolt hole 2 into alignment with the transverse space in the member C in which the device D is positioned. The shims 3 can either be adjusted so that two of said shims form a 30 space or abutment surface for the tapered device D, or one of said shims can be arranged in opposed relation to one end wall of the pocket in which said shims are positioned, so as to form a space or abutment 35 surface for the device D.

One convenient way of constructing my improved rail joint adjuster is to provide the member C with a thickened portion that laps over the rail B and form a notch or 40 recess in said thickened portion that extends transversely across the entire width of same, the upper side of said notch being closed by a cover plate 4 that is retained in position by nuts 5 which are mounted on studs 6 45 that project upwardly from the thickened portion of the member C through holes in the cover plate 4. The shims 3 consist of flat metal plates arranged edgewise transversely of the thickened portion of the member C, 50 and the combined thickness of said plates is less than the length of the pocket in which they are positioned, so that when two of said plates are arranged in spaced relation, or one of said plates is arranged in spaced 55 relation with one end wall of the pocket, a space will be formed that is just wide enough to receive the tapered device D. As the ends of the shims 3 are exposed, as shown in Figure 1, they can be adjusted easily longitudinally of the pocket in the member C, and in order to prevent said shims from shifting laterally out of said pocket, the shims are provided on their top and bottom edges with extensions 3^a, as shown in Figure 3, that 60 project into slots or grooves formed in the

cover plate 4 and in the bottom of the pocket in the thickened portion of the member C, as shown in Figure 3.

To install the adjuster, the rail joint members, splice bars or fish plates are first removed from the rails A and B, and the rail spikes are loosened sufficiently to permit the rails to move longitudinally of the ties on which they rest. The member C is then arranged on the outside of the rails and secured to the web of the rail A by bolts 1, and a few rail spikes 7 are then driven into the ties on the gauge side of the rails in proximity to the ends of the rails, so as to resist lateral movement of the rails during the adjusting operation. Obviously, any other suitable means can be used in place of the spikes 7 to resist lateral movement of the rails. The shims 3 are then adjusted longitudinally of the pocket in the thickened portion of the member C, so that two of said shims or one shim and one end wall of said pocket will be separated by a space that is slightly out of transverse alignment with one of the bolt holes 2 in the web of the rail B. The tapered device D is then introduced into said space with the end of same projecting into the bolt hole 2 in the web of the rail B, and thereafter said device D is driven transversely of the member C and rail B, so as to cause the tapered portion of said device to exert pressure on the edge of said bolt hole in a direction to produce relative longitudinal movement between the rail B and the member C that extends alongside of same. Only a slight endwise movement is imparted to the rail B each time the device D is driven home, and whenever the rail B is to be moved a considerable distance, either 70 towards or away from the rail A, it is necessary to move the rail progressively or with a step by step movement, by changing the position of the shims 3 after each time the tapered device D has been forced into the bolt hole in the web of the rail B. The device D can be of any preferred cross-sectional shape; it can be provided with a taper of any preferred angle, and it can either consist of a straight tapered pin or a pin provided with an inclined surface. Preferably, the device D is provided at its outer end with a head piece 8 that is adapted to be engaged by a maul or heavy hammer in the operation of forcing said device through the slightly offset passageways or openings in the member C and in the web of the rail B during the operation of adjusting the rails. As previously stated, I wish it to be understood that my broad idea contemplates equipping the portion of the member C that extends alongside of the rail B with any suitable kind of a means that will form an abutment surface or passageway for the tapered device D and which is capable of being adjusted relatively to the bolt hole in the 75 80 85 90 95 100 105 110 115 120 125 130

web of the rail B through which the device D passes, so as to vary the degree of movement imparted to the rail at each operation of the device D and to enable one rail to be moved longitudinally relatively to the other a considerable distance progressively or by a step by step movement. Moreover, when the adjuster is equipped with shims or filler plates that are adapted to be arranged in various positions on the member C, it is immaterial how said shims are supported by or mounted in the member C.

A rail joint adjuster of the kind above described is light enough in weight to be carried by one man; it can be operated by one man quickly and easily to increase or decrease the width of the joint between the ends of two rails; it is arranged entirely below the tread surface of the rails, preferably on the outside of the track, and consequently, does not have to be removed from the rails when a train passes over the joint; it does not interfere with the insertion or removal of an insulating end post between the rails, because the gauge side of the rails is clear and not obstructed by any portion of the adjuster, and it is of exceptionally rugged design, is inexpensive to construct and is capable of being operated by one man for closing up a joint or space of several inches in length, between the ends of two longitudinally aligned rails.

Having thus described my invention, what I claim as new and desire to secure by Letters Patent is:

1. A rail joint adjuster, comprising a member adapted to be connected to one rail in such a position that a portion of said member extends alongside of the other rail, and a tapered device that is adapted to be forced into engagement with surfaces on said other rail and on said member located below the tread surface of the head of the rail and disposed so as to produce relative longitudinal movement between said other rail and member.

2. A rail joint adjuster, comprising a member that is adapted to be connected to one rail so that a portion of said member projects alongside the web of the other rail, an opening or passageway in said member located below the tread surface of the head of the rail and arranged in offset relation with a bolt hole in the web of the other rail, and a tapered device that is adapted to be forced through said passageway and bolt hole so as to produce relative longitudinal movement between said rail and member.

3. A rail joint adjuster, comprising a member adapted to be connected to one rail so that a portion of said member laps over the web of the other rail, an adjustable abutment means on said member located below the tread surface of the head of the rail, that is adapted to be arranged in slightly offset

relation with a bolt hole in the web of said other rail, and a tapered device that is adapted to be arranged in engagement with said abutment means and driven into said bolt hole so as to exert pressure on the edge of said bolt hole in a direction to produce relative longitudinal movement between said rail and member.

4. A rail joint adjuster, comprising a member adapted to be connected to the web of one rail in such a position that a portion of said member laps over the web of the other rail, a longitudinally adjustable means on said portion located below the tread surface of the head of the rail, that forms a space which is arranged in offset relation with a bolt hole in the web of the rail overlapped by said portion, and a tapered device that is adapted to be driven through said space into said bolt hole, for the purpose described.

5. A rail joint adjuster, comprising a member adapted to be arranged alongside of two longitudinally aligned rails below the tread surfaces of same, means for connecting said member to one rail, and a device that is adapted to be moved transversely of said member and the other rail so as to engage surfaces on said member and other rail located below the tread surface of the head of the rail, and thus exert pressure on same in a direction to produce relative longitudinal movement between said member and said other rail.

6. A rail joint adjuster, comprising a member adapted to be arranged at one side of two longitudinally aligned rails across the joint between the ends of same, said member being located entirely below the tread surfaces of the rails, means for connecting said member to the web of one rail, a tapered device that is adapted to be moved transversely of said member into a bolt hole in the web of the other rail, and an adjustable means on said member located below the tread surface of the rail and disposed in such relation to said bolt hole that the pressure exerted by said tapered device on said adjustable means and on the edge of said bolt hole produces relative longitudinal movement between said member and the rail through which said tapered device passes.

7. A rail joint adjuster, comprising a member adapted to be connected to the web of one rail so that a portion of said member projects along the web of the other rail, a pocket in said portion, adjustable elements in said pocket adapted to be arranged to form a transverse passageway in said portion, and a tapered device that is adapted to be forced through said passageway into a bolt hole in the web of the rail overlapped by the said portion of said member.

8. A rail joint adjuster, comprising a member detachably connected to the web of

one rail and provided with a portion that extends alongside the web of the other rail, a pocket in said portion located below the tread surface of the head of the rail, a plurality of transversely-disposed shims in said pocket that are capable of being arranged in different positions in the pocket so as to form a passageway that is slightly offset with relation to a bolt hole in the web of the rail alongside of which said portion extends, and a tapered device adapted to be driven through said passageway and bolt hole, for the purpose described.

9. A rail joint adjuster, comprising a member adapted to be secured to the web of one rail so that a portion of said member laps over the web of the other rail, a pocket in said portion located below the tread surface of the head of the rail, transversely-disposed shims or filler plates positioned edgewise in said pocket and adapted to be arranged in different positions so as to form a passageway that is in offset relationship with a bolt hole in the web of the rail overlapped by said portion, and a tapered device adapted to be driven into said passageway and bolt hole, for the purpose described.

10. A rail joint adjuster, comprising a member constructed so as to fit between the head and base flange of one rail in engagement with the web of the rail, means for connecting said member to said rail, a thickened portion on said member that laps over

the web of the other rail and which is located entirely below the tread surface of the head of the rail, a pocket in said thickened portion, devices in said pocket, adjustable from the exterior of said member, and adapted to be arranged in different positions so as to form a passageway that is slightly offset with relation to a bolt hole in the web of the rail alongside of which the thickened portion of said member extends, and a tapered device adapted to be forced through said passageway and bolt hole.

11. A rail joint adjuster, comprising a member constructed so as to fit between the head and base flange of one rail, bolts for securing said member to the web of the rail, a thickened portion on said member located entirely below the tread surface of the head of the rail and extending alongside the web of the other rail, a pocket in said thickened portion, a removable cover plate for said pocket, transversely-disposed shims or filler plates in said pocket, adapted to be arranged in different positions so as to form a passageway that is offset slightly with relation to a bolt hole in the web of the rail alongside of which the thickened portion of said member projects, and a tapered device adapted to be driven into said passageway and bolt hole.

JOHN H. MORGAN.
